UNITED STATES PATENT OFFICE.

WILLIAM D. TORME, OF CHICAGO, ILLINOIS, ASSIGNOR TO ANNA E. HIRSCH, OF CHICAGO, ILLINOIS.

DETACHABLE CUFF.

Application filed April 16, 1924. Serial No. 706,957.

This invention relates to garments, and more particularly to detachable cuffs, an important object thereof being to provide a garment having a novel means whereby cuffs 5 may be detachably secured to the sleeve in such a manner that they may be quickly reversed to present a clean outer side or surface.

A further and equally important object of 10 the invention is to provide a fastening means for cuffs which when applied will not bulge and which will not in any way interfere with laundering of the sleeve or cuffs.

A final but nevertheless essential object of 15 the invention is to provide a garment of the character specified which is of highly simplified construction, durable in use and cheap to manufacture.

Other objects and advantages will be apparent during the course of the following description.

In the accompanying drawing forming a part of this specification, and in which like numerals designate like parts,

25 Figure 1 is a perspective view of the cuff, the novel fastening means and the sleeve, arranged in the order of their assembly, the cuff being partly broken away;

30 Fig. 2 is a perspective view—from the opposite direction—of the parts referred to in assembled state, the sleeve being in this instance partly broken away; and

35 Fig. 3 is a perspective view—on a smaller scale—illustrating the manner of reversing the cuff while in service.

In the drawing, the numeral 5 denotes a 40 sleeve having a forward hemmed end 5^a provided with the customary buttonholes 5^b. Applicable to the end of the sleeve is a typical soft cuff 6, which is folded longitudinally along a medial course—as indicated at 6^a—to define inner and outer folds. These are perforated with the usual buttonholes 6^b to cooperate with the buttonholes 5^b of the 45 sleeve when the cuff and sleeve are assembled per Figure 2, preparatory to securing them at the front by a button.

50 My invention applies at the rear portion of the cuff and sleeve assembly, and while primarily a fastening means, constitutes in effect a swivel connection to permit the cuff to be turned—and therefore reversed—relative to the sleeve without detaching it from the latter.

55 In carrying out the improvement at the

rear portion of the cuff and sleeve assembly, that fold of the cuff 6 which is applied next to the sleeve end 5^a is sewed on both sides with arched straps 6^c and 6^d of stout thread, these being alike and in a direction transverse to that of the sleeve. The rear portion of the sleeve end 5^a is sewed on its outer surface with the base of an elongated loop 5^e, the same, of course, being in proximity to the outer strap (6^c) of the cuff when the latter has been fitted over the sleeve end as illustrated in Figure 2. A connection is now made between the loop 5^e and the strap 6^c by means of a novel button 7. This button comprises a flat disk of pressed paper or fibre having oppositely arranged undercut or dovetailed notches 7^a. The disk is thus composed of opposed T-sections with a common web, and in making the contemplated connection, one of these sections is hooked in the strap 6^c of the cuff 6, while the other is hooked in the bright portion of the sleeve loop 5^e, as clearly shown in Figure 2.

55 A substantial connection is thus made at the rear portion of the cuff and sleeve assembly. The strap 6^c or the loop 5^e cannot ordinarily become detached from the button, because the notches 7^a in the latter have restricted openings, and also because any tension brought to bear on the parts will serve to more fully draw the strap or loop into the corners of the notches in the button and therefore exert a firmer hold on the latter.

60 The loop 5^e forms a means for reversing the cuff after its exposed surface has become soiled, without necessitating the removal of the cuff from the sleeve. To effect a reversal, the cuff is simply unfolded to extend as a sheet, as indicated in Figure 3, and swung through a half-turn as suggested by the directional arrows, and with the loop 5^e as a pivot. The clean side of the cuff is now 65 fully apparent, and the cuff may be again folded in the natural outward direction, fully concealing its soiled sections, and then buttoned-up in front as usual. It is significant that this action requires no handling or adjustment of the rear connection, the loop 5^e developing a single twist as the cuff is rotated; also, as but one hand is necessary to manipulate the cuff, the operation does not require the assistance of another person.

70 The provision on the cuff of the strap 6^d in addition to—and on the reverse side of—the strap 6^c is to permit either side of the 110

cuff to be applied to the sleeve end, with a strap handy for connection to the loop 5 through the agency of the button 7.

A connection is thus had which not only 5 serves as an auxiliary fastening for the cuff to the sleeve, but as a simple and efficient expedient for the handy reversal of the cuff. The connection is applicable at trifling cost, is not bulky, and once the button is detached 10 may be laundered along with the attendant garments without any interference.

Having thus described the invention, what I claim is:

1. The combination with a sleeve having 15 a cuff attaching loop on its forward edge, of a reversible cuff, and means on said cuff for detachable connection with said loop, whereby the cuff may be turned by twisting the loop while in service.

20 2. The combination with a sleeve having an attaching loop at the forward portion

thereof, of a reversible cuff, and a member secured to said cuff adjacent one edge thereof and having opposed edge recesses to receive the bight portion of said sleeve loop 25 whereby to attach the cuff to the sleeve in such manner as to permit the cuff to be turned by twisting the loop while in service.

3. The combination with a sleeve having an attaching loop at the forward portion thereof, of a reversible cuff, a member secured to said cuff adjacent one edge thereof and having opposed edge recesses to receive the bight portion of said sleeve loop 30 whereby to attach the cuff to the sleeve in such manner as to permit the cuff to be turned by twisting the loop while in service and the edge recesses of said member having constricted inlets to thereby confine the bight portion of said loop therein.

In testimony whereof I affix my signature.

WILLIAM D. TORME.
